Primary Examiner — Mary Ann Calabrese*Assistant Examiner* — Catherine Ho(74) Attorney, Agent, or Firm — JoAnn M. Seaton; Griffiths & Seaton PLLC(57) CLAIM

The ornamental design for a hanging marketing display, as shown and described.

DESCRIPTION

FIG. 1 is a front, perspective view of a hanging marketing display, showing my new design;

FIG. 2 is a bottom, perspective view thereof;

FIG. 3 is a front view thereof;

FIG. 4 is a back view thereof;

FIG. 5 is a right, side view thereof;

FIG. 6 is a left, side view thereof;

FIG. 7 is a top view thereof; and,

FIG. 8 is a bottom view thereof.

In the drawings, the broken lines depict portions of the hanging marketing display forming no part of the claimed design.

1 Claim, 6 Drawing Sheets(56)
